UNITED STATES PATENT OFFICE.

JOHN VICARS, THE ELDER, OF BOOT, AND THOMAS VICARS AND JOHN VICARS, THE YOUNGER, OF LIVERPOOL, ENGLAND.

MECHANICAL STOKER.

SPECIFICATION forming part of Letters Patent No. 606,607, dated June 28, 1898.

Application filed December 21, 1897. Serial No. 662,928. (No model.) Patented in England November 30, 1895, No. 22,929.

To all whom it may concern:

Be it known that we, JOHN VICARS, the Elder, residing at Boot, in the county of Cumberland, and THOMAS VICARS and JOHN VICARS, the Younger, residing at Liverpool, in the county of Lancaster, England, subjects of the Queen of Great Britain, have invented new and useful Improvements in and Connected with Mechanical Stokers, (for which we have obtained a patent in Great Britain, No. 22,929, bearing date November 30, 1895,) of which the following is a specification.

This invention relates mainly to furnaces in which mechanically-operated appliances for feeding and conveying the fuel into and through the furnace are employed; and it consists in improved apparatus for reciprocating fire-bars endwise, as hereinafter more fully described, and set forth in the claims.

In the drawings, Figure 1 is a sectional side elevation of the fire-bars and their connections. Fig. 2 is a partial plan view of the same, and Fig. 3 is a sectional detail showing the device for adjusting the motion of the bars.

In the drawings, referring to Figs. 1 and 2, 1 1^a are fire-bars resting alternately on cross-bearers 2 2^a.

3 4 are reciprocating keys or yokes attached at one of their ends to the cross-bearers 2 2^a, respectively, and at their other ends surrounding the driving-shaft 5. A pair of each of these keys are used, one of each pair at each end of the cross-bearers at the sides of the furnace.

6 is a tooth on the key 3, against which, as the shaft 5 rotates, a dog or projection 7 acts, so as to push forward the said key with cross-bearer 2 and attached fire-bars 1. The cross-bearer 2 in its forward motion comes against shoulders 1^c on the fire-bars 1^a and carries them forward with it and also the cross-bearer 2^a and key 4. As the shaft 5 continues to rotate the dog 7 comes against a tooth 8 on the key 3 and draws such key backward, together with cross-bearer 2 and fire-bars 1, the key 4, cross-bearer 2^a, and fire-bars 1^a being meanwhile prevented from moving backward by

the stop 9 on the key 4 coming against the cam 10 on the shaft 5. As the shaft 5 rotates still further the cam 10 is disengaged from the stop 9, and a dog or projection 11 on the shaft 5 comes against a tooth 12 on the key 4 and moves such key backward, together with the cross-bearer 2^a and fire-bars 1^a. The operation is then repeated. Any convenient means of driving the shaft 5 may be used, as is well-known. By the above means a positive and certain alternate backward motion is given to the fire-bars.

Referring particularly to Fig. 3, in order to allow of a varied travel being given to the fire-bars we attach the teeth 6 of the pair of keys 3 to bars 13, free to slide in guides in the said keys 3 and secured in position by pawls 14, taking into racks 15 on the bars 13. By drawing out the bars 13 in the direction of the arrow the dogs 7 come in contact with the teeth 6 sooner, and greater forward travel is given to the keys 3 and thereby to the whole of the fire-bars, the return motion being as before described, or if the friction between the alternate fire-bars 1 1^a is sufficient the fire-bars 1^a are free to travel back with the bars 1 until the stops 9 on the keys 4 come against the cams 10, thereby bringing the bars 1^a to rest until, by rotation of the shaft 5, the cams are freed from the stops 9, when the remainder of the back travel of the bars 1^a is caused by the dogs 11, as before described. By this means whatever may be the forward travel of the fire-bars during a certain fixed portion of the back travel the bars must move alternately. When the adjustable bars 13 are employed, we prefer to make the cams 10 of shorter throw than when fixed teeth 6 are used on the keys 3.

The fire-bars 1 1^a are made with the rear portions 1^b detachable and secured to the front portions by projections 20, fitting into recesses 21, so that the rear portions can be renewed when worn independently of and without disturbing the front portions.

22 are V-joints for preventing lateral movement of the rear portions.

23 is a bar or bearer attached to the sides

of the furnace at 24 for supporting the fire-bars at the junction of the front and rear portions.

25 is the usual bar for supporting the back 5 end of the rear portion of the fire-bars.

We claim—

1. In a mechanical stoking apparatus, a set of fire-bars alternately connected to separate cross-bearers, a rotatory shaft having actuating connections with the bearers, arranged to give a single forward, and alternate backward motion to the fire-bars, and a cam upon the shaft arranged to hold one set of bars against backward movement during a portion of the 15 rotation; substantially as described.

2. In mechanical stoking apparatus, the combination with a set of fire-bars, of separate cross-bearers connected to alternate fire-bars, one series of bars having keys 3 with 20 teeth 6 and 8, a rotating shaft having projections arranged to act upon the teeth, and keys 4 having teeth acted upon by projections on the shaft, and connected with the other fire-bars, and stops upon one series of bars 25 arranged to contact with a cam upon the shaft, to prevent backward motion of the series during a part of the revolution of the shaft; substantially as described.

3. In mechanical stoking apparatus, the 30 combination with a rotary shaft having projections or dogs, of separate keys having projections engaged by the dogs, at least one of the key projections being located upon an adjustable bar carried in the key, and fire-bars

connected alternately to cross-bearers actuated by the keys, the connection being arranged to give a single forward motion of variable extent, and alternate backward motion to the fire-bars; substantially as described. 35

4. In mechanical stoking apparatus, a set 40 of fire-bars alternately connected to upper and lower cross-bars, actuating connections between the cross-bars and a rotatory shaft, the cross-bar of one set of fire-bars being arranged to move the other bars forward, and a 45 cam upon the shaft arranged to prevent rearward movement of one set of bars during a portion of the rearward stroke of the other bars, substantially as described.

5. In mechanical stoking apparatus, a fire- 50 bar made in two parts, one of said parts having an end groove and a vertical slot, and the other part having a lug to enter the slot, and a reduced end portion arranged to fit in the groove and prevent side movement, and a 55 support for the bar located beneath this loose connection; substantially as described.
